JULY 5

UNITED STATES PATENT OFFICE.

JOHN G. HAYES, OF EL PASO, TEXAS.

AIR-BRAKE ANGLE COCK.

Application filed May 4, 1923. Serial No. 636,544.

This invention relates to improvements in angle-cocks, for train air brake systems, of the class commonly used to connect the air hose to the train pipe line between the cars, 5 and is intended to be used with standard air brake equipment now in use and with the modern cross-compound pumps that are designed to overcome small air leaks in the air lines and couplings.

10 Objects of the present invention are: to provide an angle-cock that will cause draining of the air, from both sides of the angle-cock, should the plug become partially turned to cut-off position, thereby causing 15 the brakes to be set so that the train cannot start until all angle-cocks are turned to the full "on" position, i. e., the position in which there is an uninterrupted path for the air to flow through the train line to prevent the 20 brakes from becoming applied or set; the provision in such an angle-cock for the air to flow from the front of the train line, with resultant application of the brakes, should the plug be turned to full cut-off position at 25 the front of any car; the provision of such an angle-cock that will drain the train line from the rear of any car to the caboose should the cock become fully cut-off at the 30 rear of any car; the provision of an angle-cock that will so reduce the air that no modern cross-compound pump will overcome it when the plug is turned towards 35 cut-off position; the provision of such an angle-cock that will accomplish the above-mentioned objects and yet does not require additional means to close the train pipe line when a car is detached from the rest of the train; and such other improvements and advantages in construction and operation as 40 are found to obtain in the structure herein-after described and claimed.

In the accompanying drawings, forming a part of this specification, and showing, for purposes of exemplification, a preferred 45 form and manner in which the invention may be embodied and practiced, but without limiting the claimed invention specifically to such illustrative instance or instances:

50 Figure 1 is a side elevation of an angle-cock embodying the present invention;

Fig. 2 is a central vertical section through the same;

55 Fig. 3 is a top plan view of the same, indicating the position of the handle when

the plug is at a partial position and at a full cut-off position;

Fig. 4 is a horizontal section taken through the plug and casing, and showing the plug in the "on" position, and the positions of the ports and passages in the "on" position;

Fig. 5 is a horizontal section taken through the plug and casing, and showing the plug in partial cut-off position, and 65 showing the positions of the passage and ports in such partial cut-off position;

Fig. 6 is a horizontal section taken through the plug and casing, showing the 70 position of the plug in full cut-off position, and the arrangement of the plug passage and the plug and casing ports in such final cut-off position.

In the embodiment illustrated in the drawings, the invention is incorporated in 75 an angle-cock that is designed for railway air brake appliances. For convenience, the present description will be confined to the illustrated embodiment of the invention; features of the invention are, however, susceptible of other valuable applications; hence, the invention is not confined in scope 80 to the specific use and embodiment herein described as an illustrative example.

In the illustrated embodiment of the invention there is shown on the drawings an angle-cock of the usual standard design, comprising, a casing 10 having one end 11 adapted to be connected with the train pipe 12, and having the usual downwardly extending portion 13 at its other end adapted to be connected with the usual hose member 14. For convenience, the end 11 will be referred to as the train pipe side, and the end 13 will be referred to as the hose pipe 95 side. The casing is centrally bored at the top 15 and bottom 16 to receive a rotatable plug 17, having a head 18 upon which a handle 19 is positioned to rotate said plug to "on" and "cut-off" positions. The handle 100 19 is provided with a downwardly extending projection 20 adapted to make contact with a stop 21 when the plug is in the "on" position and also to make contact with another stop 22 when the plug is rotated to full 105 cut-off position. The casing is centrally bored so as to provide inclined surfaces 23 to receive the plug 17 which is also given a tapered form so that when it is inserted into the casing through the opening in the bottom 110

16 no additional securing means will be necessary at the top 15 of the casing to maintain the plug in position. The bottom 24 of the plug is provided with an annular projection 25 providing a surface 26 against which a tension spring 27 bears. The lower end of said spring 27 is contained within a pocket 28 of cap 29 that is screwed onto the bottom 16 to close said opening and maintain said plug in air-tight engagement with said casing.

The casing 10 has an outlet port 31, preferably about $\frac{1}{2}$ inch in diameter, in one side thereof, and said port is off-set with respect 15 to the center of the plug 17 in order that a communication may be made between the elongated central plug passage 32 and the outlet casing port 31, upon rotation of the plug either to partial or complete cut-off 20 position. The passage 32 affords communication for air from either the hose side to the train pipe side, or vice versa, when the plug is rotated to the "on" position, as shown 25 in Fig. 4, thereby affording an uninterrupted path for the air in its passage through the casing passageway 33. The passage 32 in the plug is defined by the sides 34 and 35 of the plug and in the side 34 there is provided a port 36, located below the plane of the 30 casing port 31, that is off-set with respect to the center of said plug, towards the hose pipe side, a distance sufficient that, when the plug is partially rotated, as shown in Fig. 5, an amount sufficient to partially cut off the 35 hose pipe side from the train pipe side the air will pass through the port 36 to the passage 32 and out through the outlet port 31 and at the same time the air from the train pipe side will pass into the passage 32 and out through the outlet port 31 and cause a 40 reduction in the amount of air which, with the modern air brake systems now in use, will cause the brakes to be set on all of the cars, both to the rear and to the front.

45 Should the plug be rotated to substantially full cut-off position, then the side 35 of the plug will seal the train pipe side, but the hose pipe side will bleed, as shown in Fig. 6, through ports 36, passage 32, and outlet port 50 31, causing continued application of the brakes, towards the hose pipe side, until the plug is rotated to "on" position, as shown in Fig. 4. It will be apparent, therefore, that should the plug be given a partial turn the 55 train pipe will bleed from both sides of the angle-cock; but should the angle-cock be positioned on the rear of any car, and the plug be turned to full cut-off position, it will drain the train line from said rear end clear 60 to the caboose and cause the brakes to be applied. Should the angle-cock be positioned at front of any car, and the plug turned to full cut-off position, it will seal the train pipe side and bleed the train line from the 65 front of such car clear to the locomotive and

cause application of the brakes. It will also be apparent, from the foregoing description, that an angle-cock constructed in accordance with this invention having ports of substantially the dimension mentioned will be effective in reducing the pressure in the air lines in sufficient amount to cause application of the brakes and continue to so reduce the air that no modern cross-compound pump will overcome such bleeding, and it will 70 also be apparent that, when a car is cut off, for instance in switching cars in the yards, no additional cap will be required to seal the train pipes, for when the plug is turned to full cut-off position the side 35 of the plug 75 will seal such train pipe line.

The invention as hereinabove set forth is embodied in a particular form but may be variously embodied within the scope of the claims hereinafter made.

I claim:

1. In an angle-cock, the combination with the valve casing having a port in one side and an air passage leading therethrough from the hose side to the train pipe side; of a rotatable plug in said casing, said plug having a central passage opening therein, said plug also having a port leading through one side of said plug to said passage opening, said plug port being off-set with respect to the center of said plug so that upon rotation of said plug an amount sufficient normally to cut off said cock from the hose side the air will pass through said port to the air passage opening in said plug and out to the atmosphere through the port in the casing; the air passage opening in said plug being of sufficient width to allow the air from the train pipe side to pass out through the casing port, together with the air from the hose side, upon rotation of said plug to any cut-off position except full cut-off position and when said plug is turned to full cut-off position the train pipe side is then sealed by said plug in such full cut-off position.

2. In an angle-cock, the combination with the casing, of a rotatable plug therein, said casing having a passage leading from the hose pipe side to the train pipe side; said casing also having a port in one side, said port being off-set with respect to the center of said plug; said plug having an air passage opening therein to allow flow of air through said casing when said plug is rotated to the on position, said plug opening communicating with said casing port upon rotation of said plug towards cut-off position; said plug also having a port in one side, off-set with respect to the center of said plug, a distance sufficient to cause a path for the air from the hose side, through said plug port, said plug passage opening, and said casing port, upon rotation of said plug an amount sufficient to cause said hose pipe side to be cut off from said angle-cock;

said plug passage opening being arranged to allow passage of air from the train pipe to said casing port, at the same time that the air is passing through the plug port, upon 5 rotation of the plug an amount sufficient to substantially cut off the hose pipe side from said train pipe side, except when the plug is turned substantially to full cut-off position, and then said plug seals the train pipe side 10 to stop passage of air therefrom but allows passage of air from the hose pipe side through said plug port, plug passage and casing port out to the atmosphere.

3. In an angle-cock, in combination: a 15 casing; a plug therein; said casing having a port therein; said plug having a passage therein permitting communication from a hose pipe through the plug to the train pipe; a port in one side of said plug allowing air 20 to pass to the plug passage and then to the casing port when the plug is turned to any substantially cut-off position; said plug passage being arranged in said plug so as to allow passage of air from the train pipe side 25 to the casing port when the plug is rotated to any substantially cut-off position except full cut-off position when the train pipe side is then sealed at such full cut-off position.

4. In an angle-cock, in combination: a 30 casing; a plug in said casing; said casing having a port therein; said plug having a passage therein to permit communication through said plug when said plug is in the on position, said plug having a port therein 35 communicating with said plug passage; said plug passage communicating with said casing port when the plug is rotated any amount sufficient to substantially cut off the passage from one end of said casing to the other; both said ports being arranged to overcome modern cross-compound pumps and cause application of brakes and to indicate to the engineer that an angle-cock is 40 either in partial or full cut-off position.

45 5. In an angle-cock, in combination: a casing; a plug in said casing; said casing having a port therein; said plug having a passage therein to permit communication

through said plug when said plug is in the "on" position; said plug having a port 50 therein communicating with said plug passage; said plug passage communicating with said casing port when the plug is rotated an amount sufficient to cut off the passage of substantial amount of air from one end of 55 said casing to the other; both said ports being arranged to overcome modern cross-compound pumps and drain the train line from locomotive to caboose when the valve is partly cut off.

6. In an angle-cock, in combination: a 60 casing; a plug in said casing; said casing having a port therein; said plug also having a passage therein to permit communication through said plug when said plug is in the "on" position; said plug having a port 65 therein communicating with said plug passage; said plug passage communicating with said casing port when the plug is rotated an amount sufficient to cut off the passage of 70 substantial amount of air from one end of said casing to the other; both said ports being arranged to overcome modern cross-compound pumps and drain the train line 75 from the rear of any car to caboose upon complete cut off of said valve at the rear of any car.

7. In an angle-cock, in combination: a 80 casing; a plug in said casing; said casing having a port therein; said plug also having a passage therein to permit communication through said plug when said plug is in the "on" position; said plug having a port 85 therein communicating with said plug passage; said plug passage communicating with said casing port when the plug is rotated an amount sufficient to cut off the passage of substantial amount of air from one end of said casing to the other; both said ports being arranged to overcome modern cross-compound pumps and so reduce the air and thereby cause application of the brakes on 90 the cars towards the front of the train should the angle-cock become completely cut off at the front of any car.

JOHN G. HAYES.
